MULTIPLE GARMENT HANGER

Alma P. Swanson, Inglewood, Calif.

Application April 5, 1946, Serial No. 659,747

8 Claims. (Cl. 223—91)

1

This invention relates to clothes hangers and more particularly to a multiple unit hanger upon which a plurality of garments or types of garments may be hung simultaneously.

Hangers of customary construction comprise arcuate shoulders formed of a stick or wire, sometimes including a straight lower stick or wire joining the lower ends of the arcuate shoulders. Conventional type hangers can accommodate only one or two garments at one time such as a coat and pants unless the garments are placed one over the other and hung by their shoulders. In that event, it is necessary to remove the uppermost garment before removing the one underneath it. Even when using the straight lower member as for hanging trousers, a second pair of trousers draped over the first must be removed before the trousers underneath are accessible.

It is a purpose of this invention to provide a novel hanger by which several garments may be conveniently hung simultaneously and independently upon the same hanger body.

Essentially the invention contemplates the provision of a hanger body of substantial depth formed with a plurality of grooves in spaced horizontal relation upon the opposite faces thereof. Suitable fingers of resilient material are fastened to the hanger body for pivotal spring pressed engagement over the respective obverse and reverse faces of the hanger body for gripping engagement with any one or more of the horizontal grooves.

Having these features in mind, it is an object of this invention to provide a hanger upon which several garments may be simultaneously and independently hung and from which one may be removed without interfering with the other garments.

It is another object of this invention to provide a hanger unit which will result in a conservation of closet space by avoiding the duplication of hangers corresponding to the number of garments.

A further object of this invention is to provide a new and improved hanger construction which can adjustably accommodate either heavy or light garments.

A still further object of this invention is to provide a new and improved hanger construction adapted to receive either large or small garments with substantially equal facility.

Another further object is to provide a new and improved hanger upon which each garment may be hung in a folded or stretched condition and also upon which a plurality of light garments may be

2

collectively supported without interfering with other garments separately supported.

It is also an object of this invention to provide an improved means by which a plurality of articles may be conveniently hung for airing.

An additional object is to provide a suitable improved hanger for garments such as skirts, underwear, hats and the like which cannot readily be hung upon hangers of conventional construction.

With these and other objects in view, the invention consists in the construction, arrangement and combination of the various parts of the device whereby the objects contemplated are attained, as hereinafter set forth, pointed out in the appended claims and illustrated in the accompanying drawings.

In the drawings:

Figure 1 is a front view of a hanger embodying this invention.

Figure 2 is a top view of the same.

Figure 3 is an end view taken as from the left-hand side of Figure 1.

Referring more particularly to the drawings there is shown a hanger body generally designated by the numeral 10 formed with arcuate shoulders 11 and 12 substantially similar in shape and proportions to those in a hanger of the usual construction. The opposite faces 13 and 13' are provided with a plurality of horizontal vertically spaced grooves including an uppermost set of grooves 14 and 14', a second set of grooves 15 and 15', a third set of grooves 16 and 16' and a fourth or lowermost set of grooves 17 and 17', respectively.

Spaced inwardly from lateral edges 18 of the hanger body and in a position above the uppermost groove are holes 19 through the hanger body accommodating pins 20 and 21 which protrude upon opposite sides of the hanger body. Each pin has a head 22 on one end and a head 23 on the opposite end for the purpose of pivotally confining a set of spring fingers 25, 26 and 27 upon the obverse face of the hanger body and a similar set of spring fingers 28, 29 and 30 upon the reverse side. Similar sets of such spring fingers are provided upon both the left and right hand sides of the hanger body in mutually spaced apart relationship. The tips 32 of the fingers are suitably curved for engagement within the grooves under the spring tension of the fingers.

The fingers are superimposed over one another at the pin upon each side of the hanger body and are bowed outwardly to a decreasing extent from the innermost finger 27 to the outermost finger

25, for example, for the two-fold purpose of providing a clearance for the resilient fingers between themselves and also for any garments which are hung between the fingers and the body.

At the top of the hanger body is an axially disposed hook 33 provided for the usual purpose of supporting the hanger upon a clothes pole.

The body of the hanger can be formed with a flat surface as well as a corrugated one, although corrugations are preferable in that they cooperate with the ends of the fingers in supporting the garment by decreasing the amount of direct pressure which must be exerted between the spring fingers and the body to sustain a given amount of garment weight. The grooves or corrugations may be continuous, short or even round so as to take the form of a mere recess or depression and may be variously spaced apart whether evenly or otherwise.

The main body of the hanger may be formed 20 of wood, plastic material composition or equivalent substances and may be either solid or hollow in the interior portion. The hook for supporting the same may extend vertically through the full depth of the hanger body and may in that case be formed within an upset terminal end bearing against the surface of the hanger preventing the hook from pulling out of the hanger body and furnishing a bearing surface upon which the hook may swivel. In the event the hanger body is 25 hollow, the shank of the hook may be shorter so as to terminate just within the uppermost sheet comprising the upper wall of the hanger body.

If desired, whether the hanger body be hollow or solid, a suitable swivel plate may be screwed to the top of the hanger. The spring fingers may be made from flexible wooden reed, spring steel, plastic or other resilient substances and may take the form of a round rod or wire or a flat strip.

If desired, the spring fingers may be provided with rubber or plastic sleeves providing either a gripping surface or a smooth surface. The tips of the fingers need not be curved but may be flat or substantially so. If curved, they may be curved in the opposite direction so as to be engageable with ridges which may be formed upon the hanger body instead of the grooves which are illustrated.

It will thus be apparent that there has been provided a multiple hanger upon which a series of grips or spring fingers are located on opposite sides of the hanger in spaced relationship in a manner which enables them to cooperate with one another to support garments of different sizes and lengths.

It may be noted that the smooth surfaces above the grooves by means of the clips upon the upper body portion may be used for hanging hats or other articles made of stiff, substantially non-pliable material by their brims whereby they will not be bent or distorted, a condition which might occur if such stiff fabrics were forced into conformance with the contour of the grooves.

Obviously, the grips may be pivoted at their centers or mounted upon pins or the like which are slidably disposed in a groove traversing the face of the hanger body so as to change the position of the pin relative to the faces of the hanger body. Obviously, also, any number of fingers may be provided for each pin whether on one side or both sides thereof.

The resilient fingers are adapted to move past one another without interference so that each finger independently or more than one finger co-

operatively may grip a garment whether at spaced points or the same point.

The upper edge of the hanger body may be formed with a curved shoulder upon which an additional garment may be hung by the shoulders in the conventional way.

It may be noted that the use of this improved hanger in the usual manner does not prevent its contemplated use as a multiple hanger. It 10 is a feature of the invention that garments simultaneously supported thereon may be independently hung and also independently removed.

While this invention has been herein shown and described in what is presently conceived to be the most practical and preferred embodiment, it is recognized that departures may be made therefrom within the scope of the invention, which is not to be limited to the details disclosed herein but is to be accorded the full scope of the claims so as to embrace any and all equivalent devices.

The invention having been herein described, what is claimed and sought to be secured by Letters Patent is:

25. 1. A clothes hanger comprising a hanger body formed with a plurality of spaced recesses and an elongated resilient finger pivotally secured at one of its ends to the body and normally spring urged against said body, said other end of said finger being turnable about said pivotal securement for selective engagement in any of said recesses.

2. A clothes hanger comprising a hanger body formed with a plurality of spaced recesses and a plurality of elongated resilient fingers pivotally secured at one end of each to the body and normally spring urged against said body, the other ends of said fingers being rotatable about said pivotal securement for selective engagement in any of said recesses.

3. A clothes hanger comprising a hanger body formed with a plurality of spaced recesses and a plurality of sets of elongated resilient fingers, said fingers being pivotally secured at one end of each to the body and normally spring urged against said body, the other ends of said fingers being turnable about said pivotal securement for selective engagement in any of said recesses, said sets of fingers being provided in spaced pairs on the same face of the body and having selectively cooperative but independent positions of engagement upon said one side of said body.

4. A clothes hanger comprising a hanger body formed with a plurality of spaced recesses and a plurality of sets of elongated resilient fingers, said fingers being pivotally secured at one end of each to the body and normally spring urged against said body, the other ends of said fingers being turnable about said pivotal securement for selective engagement in any of said recesses, a pivot pin extending through said body from face to face thereof, said sets of fingers being jointly secured upon opposite faces of said body by means of said pivot pin.

5. A clothes hanger comprising a hanger body formed with a plurality of spaced recesses and a plurality of elongated resilient fingers pivotally secured to the body and normally spring urged against said body, the other ends of said fingers being rotatable about said pivotal securement for selective engagement in any of said recesses, a pair of spaced pivot pins extending through said body from face to face thereof, said fingers being jointly secured upon opposite faces of said

body by means of and upon each end of each of said pivot pins.

6. In combination in a hanger, a hanger body formed with an arcuate recess upon a face thereof, a pin through said body spaced from said recess and a resilient finger pivotally secured upon said pin and normally spring urged against said body, an end of said finger being engageable in said recess for clamping clothes against the face of said hanger between the end of said finger and said recess.

7. In combination in a hanger, a hanger body formed with an arcuate recess upon a face thereof, a pin through said body spaced from said recess and an outwardly bowed resilient finger pivotally secured upon said pin and normally spring urged against said body, an end of said finger being engageable in said recess for clamping clothes against the face of said hanger between the end of said finger and said recess.
